UNITED STATES PATENT OFFICE

JOHANNES HERRMANN, OF BERLIN-HALENSEE, GERMANY, ASSIGNEE TO SIEMENS & HALSKE AKTIENGESELLSCHAFT, OF SIEMENSSTADT, NEAR BERLIN, GERMANY, A CORPORATION OF GERMANY

SYNCHRONIZING SYSTEM

Application filed May 21, 1930, Serial No. 454,369, and in Germany April 13, 1929.

The invention relates to a method for the utilization of the slot frequency of the armature of commutator motors, for instance of the driving motors of picture telegraphy 5 apparatuses, as carrier frequency for the transmission of signals, in particular for the purposes of synchronization.

Up to the present the alternating currents, produced in the armature and depending on 10 the number of the slots and the number of revolutions of the armature, were considered as disturbing currents whose appearance was suppressed by various means, such as inclined 15 position of the slots, more uniform distribution of the winding on the circumference of the armature. In smaller motors with few armature slots, wherein such means for the suppression of the slot currents are not provided, the ripple of the armature current may 20 amount to 40%. The frequency of the slot alternating currents is found generally in motors with normal peripheral speed above 300 cycles, and hence offers no difficulties to the transmission over telephone lines.

25 The method of synchronizing which has been set forth according to the present invention utilizes in simple manner the frequency given by the ripple of the armature current as carrier frequency for the transmission of, for instance, a control frequency 30 to a remote station. As the control frequencies in question in this case are frequencies of the order of 50-150 cycles, they can no longer be transmitted over telephone lines 35 with intermediate repeaters.

Other objects and advantages of the invention will, of course, become apparent and suggest themselves to those skilled in the art by reading the following specification and 40 claims in connection with the accompanying drawings, wherein:

45 Figs. 1a and 1b represent principles of circuit arrangements by means of which the slot frequency may be sifted out of the armature direct current;

50 Figs. 2a and 2b represent further modifications and disclose circuits wherein the slot frequency is modulated with another frequency such as a controlling frequency; and,

Fig. 3 represents still a further modifica-

tion of the arrangement disclosed in Fig. 2b for example.

Now referring to the drawings, in Fig. 1a the armature D. C., which feeds the motor 1, is sent through the primary 2 of a transformer 3 from whose secondary 4 the slot frequency may be taken off. In Fig. 1b there is inserted instead of transformer 3 a resistance 5. The potential drop across this resistance varies in the rhythm of the slot frequency. For the blocking of the D. C., a condenser 6 is provided.

By the modification shown by Fig. 2a, the D. C. feeding the armature of motor 7 is sent, as in Fig. 1a, through the primary 8 of a transformer 9 in whose secondary is connected a resistance 10. The potential drop across this resistance 10 is conveyed over a conductor or the like to the motor, to be maintained in synchronism with the former motor, for instance the receiving motor of an installation for picture telegraphy. The secondary circuit of transformer 9 is periodically short-circuited through a contact disk 20 coupled with driving motor 7. In this manner impulses are conveyed to the motor to be watched which correspond to the modulation of the slot frequency by means of the contact disk. In place of transformer 9 there may be inserted, similar also instead of resistance 10, a resistance 11 in connection with a condenser 12, respectively a transformer 13, as illustrated in Fig. 2b.

A further manner of application of the method according to the invention is represented in Fig. 3, wherein the D. C. motor 14 is regulated in a manner known as such in the prior art by means of a control frequency conveyed to a relay 15, operating in connection with a resistance 16 connected in the armature circuit. The same control frequency is brought by means of the modulation of the slot frequency to another motor to be kept in synchronism. The modulated slot frequency is taken from the secondary side 17 of a transformer 18 connected in parallel with a periodically bridged over-resistance 16. For the blocking of the D. C., a condenser 19 is connected in the circuit of the primary. The transformer 18 conveys the slot fre-

quency, modulated with the control frequency, directly to the receiving side or through appropriate amplifiers.

The embodiment according to Figs. 2a and 5 2b may also be used for the sending of the impulse in devices which are controlled according to the start-stop system in the manner that for instance a contact disk or any other contact producing device is controlled 10 by the picture cylinder and gives the synchronizing signal in the picture seam.

Instead of the transformers and resistances as shown use may also be made of choke coils in connection with condensers for the 15 sifting and the retransmission of the slot frequencies.

The ripple of the armature current may be increased by slots in the poles of the exciter magnets.

20 The alternating currents of the slot frequency can also be utilized for the transmission of other than synchronizing signals, for instance at the starting and stopping of a picture transmission for the retransmission 25 of telegraphic signals or during operation for the transmission of start-stop signals or the like.

Having now described my invention, what I claim and desire to secure by Letters Patent 30 is the following:

1. A method for the transmission of synchronizing signals which comprises driving a picture telegraph apparatus by a driving motor and producing from the driving motor 35 a slot frequency for use as a carrier frequency for synchronizing signals.

2. In a system for the transmission of signals for synchronizing picture telegraph apparatus, a driving motor for the picture telegraph transmitting apparatus, and means 40 for obtaining from said driving motor a slot frequency for use as a carrier frequency for transmitting synchronizing signals for use at a remote point.

45 3. In a system for the transmission of synchronizing signals, a commutator motor for driving picture telegraph apparatus at the point of transmission, means for obtaining from said commutator motor the slot frequency for use as the carrier frequency for 50 synchronizing signals, and means for modulating the produced slot frequencies by a controlled frequency.

4. In a system for the transmission of synchronizing signals, a commutator motor for driving picture telegraph apparatus at the point of transmission, means for obtaining from said commutator motor the slot frequency for use of a carrier frequency of synchronizing signals, and a contact establishing device coupled with the driving motor 55 for modulating said slot frequency.

5. In a picture telegraph apparatus, means for synchronizing remotely spaced rotary bodies which comprises a commutator motor

for driving local picture telegraph apparatus, means for filtering the slot frequency of the armature current of said motor for use as a carrier frequency of synchronizing signals, and a current interrupting device associated 70 with said slot frequency filtering means for interrupting the said frequency a predetermined number of times per revolutions of the motor for modulating the slot frequency at the rhythm of the control frequency. 75

6. In a system for producing signals for synchronizing remotely spaced bodies for use in connection with picture telegraph apparatus, a commutator motor for driving local picture telegraph transmitting equipment, means for obtaining from the armature current supplied to said motor energy of a frequency corresponding to the slot frequency, and means for modulating said slot frequency at a predetermined rate prior to 80 the time of transmitting said control frequency to a remote point to control the apparatus corresponding to elements positioned at the local point.

In testimony whereof I affix my signature. 90
JOHANNES HERRMANN.
